UNITED STATES PATENT OFFICE.

WILLIAM J. CUNNINGHAM, OF PHILADELPHIA, PENNSYLVANIA.

BOTTLE-FILLING MACHINE.

No. 868,868.

Specification of Letters Patent.

Patented Aug. 18, 1897.

Application filed December 16, 1896. Serial No. 348,061.

To all whom it may concern:

Be it known that I, WILLIAM J. CUNNINGHAM, a citizen of the United States, residing in the city and county of Philadelphia, State of Pennsylvania, have invented 5 a new and useful Bottle-Filling Machine, of which the following is a specification.

My invention relates to bottle filling machines and consists of means for placing a plurality of bottles in a position beneath the filling means and actuating the 10 latter at the proper time so that the bottles are filled.

It further consists of means for automatically actuating the conveyer and stopping the same for a predetermined period.

It further consists of means for automatically raising 15 and lowering the filling devices and for holding the same in elevated and lowered position a predetermined time.

It further consists of novel details of construction, all as will be hereinafter fully set forth.

20 Figure 1 represents a side elevation of a filling machine embodying my invention, showing the frame and conveyer broken. Fig. 2 represents a vertical sectional view on line $x-x$, Fig. 4, showing a different number of filling devices from that shown in Fig. 1. Fig. 3 represents a partial elevation and partial sectional view of a portion of the device in detached 25 position. Fig. 4 represents a sectional view on line $y-y$, Fig. 1. Fig. 5 represents a view of the actuating means showing the shafts in section.

30 Similar numerals of reference indicate corresponding parts in the figures.

Referring to the drawings:—I have found in practice that in bottle filling machines it is necessary to deliver the bottles or receptacles to be filled to a position beneath the filling means and to hold the bottles in this position while the filling means are actuated to fill the bottles and that after the filling means are again closed, to remove the bottles, already filled, from their position beneath the filling means and to place another 40 set of bottles thereunder.

In the drawings I have shown a construction for accomplishing this result, but it will be evident that changes may be made therein without departing from the spirit of my invention, which will accomplish 45 the same result and I therefore do not desire to be limited in every instance to the construction as herein shown and described.

1 designates the frame of the machine which may be of any desired construction and at the opposite ends 50 of which I mount the sprockets 2 and 3 in suitable bearings in the said frame.

4 designates a wheel, to which power is applied in any suitable manner, said wheel actuating a gear 5 which is in mesh, in the present instance, with the 55 miter gear 6, which is carried by a gear shaft 7, upon which is mounted a worm 8 which is in mesh with

the worm gear 9, the latter being carried by the worm gear shaft 10 which is mounted in suitable bearings in the frame 1. Carried by the worm gear shaft 10 is the intermittent or mutilated gear 11, the teeth of 60 which mesh at the proper time with a mutilated or intermittent gear 12 carried by the sprocket shaft 13, which latter is mounted in suitable portions of the frame 1 and carries, in the present instance, the two sprockets 14 and 15 on opposite sides of the machine, 65 it being understood more especially from Fig. 5, that the intermittent or mutilated gear 11 is provided with the teeth 16 extending a short distance on its face, the remaining surface 17 of said gear 11 being plain and adapted to ride the plain surfaces 18 on the sprocket 70 shaft gear 12, at the proper time, said faces 18, in the present instance, being three in number, in order that the said sprocket shaft gear 12 will be intermittently operated as hereinafter described. Also carried on the worm gear shaft 10 is the intermittent 75 gear 20 for actuating the filling means, the intermittent gear 20 being provided with the two sets of teeth 21 and 22, in the present instance between which are the two plain surfaces 23 and 24, which in the present instance are of different extent; the said teeth 30 on the gear 20 meshing at the proper time with teeth 25 of the lifter gear 26, which is also provided in the present instance with the two plain surfaces 27 adapted to contact at the proper time with the surfaces 23 and 24 of the gear 11, as will be hereinafter described. 35 The lifter gear 26 is carried by the lifter shaft 28 which is suitably journaled in the frame 1 of the machine and which has connected therewith on opposite sides thereof, the cranks 29 carrying the crank pins 30. Connected in any suitable manner with the crank 90 pins 30 are the rods 31 on opposite sides of the machine which are provided with the collars 32 connected in any suitable manner with the rods 33, which are movable in guides in the frame 1 of the machine. 44 designates a collar which is adjustably connected 95 with the rods 33, to which are pivoted the links 35, the opposite ends of which are pivotally connected with the levers 36, the opposite ends of which are pivoted, as at 37, to a suitable portion of the frame 1 of the machine and which have pivotally connected 100 therewith intermediate their ends the tank or reservoir 38, it being noted more especially from Fig. 3 that a pin 39 forms the connection between the levers 36 and the tank 38 and that a slot 40 is provided in each of the levers 36 in order to permit proper movement of the levers as the rods 33 are raised and lowered. In the bottom of the tank 38 I provide a plurality of 105 filling means which consists of valves 41, which may be of any desired construction, but which are normally held closed by any suitable means, in the present instance by the action of the springs 42, but which are adapted to open when the heads 43 of the

filling means or valves contact with the mouth of the bottles 44, overcoming the tension of the springs and opening the valves, so that the liquid or fluid contained in the reservoir or tank 38 is permitted to flow therefrom through the valves 41 into the bottles, said valves being so constructed that as soon as the pressure is removed from the same they will automatically close and cut off the supply of liquid.

45 designates a conveyer or chain which is provided with any suitable means for holding the bottles 44. In the present instance I have shown the strips 46 carried by the conveyer between which the bottles are adapted to be seated. The conveyer passes around the sprockets 2 and 3 and over the sprockets 14 and 15, the teeth of the latter engaging in suitable links in the chain in order to actuate the same, it being noted, however, that while I have shown, in the drawings the sprockets 2 and 15 as idlers, power may be imparted to them by any suitable means, such as a belt, which receives motion from the sprockets 14 and 15 or from the sprocket shaft 13, as may be necessary. In order to properly guide the conveyer, I provide tracks 47 on each side of the conveyer carried by the frame 1, which may be of any desired construction, but which are adapted to prevent the sagging or raising of the conveyer so that it prevents the links from being disengaged from the teeth of the sprockets 14 and 15 and at the same time will always present the bottles 44 in the proper position with respect to the filling means or valves 41.

30 In describing the operation of the machine I will first show how the carrier or conveyer is intermittently actuated, that is to say, how the bottles are brought beneath the filling means and held there a predetermined time and then moved forward after being filled. When power is imparted to the power wheel 4 it actuates the gear 5 and miter gear 6, which rotates the gear shaft 7 and worm 8 and the worm gear 9 is rotated, carrying with it the worm gear shaft 10. This imparts motion to the intermittent gear 11 and rotates the same. When one of the faces 18 of the sprocket shaft gear 12 is in contact with the plain face 17 of the gear 11 no motion will be imparted to the carrier 45, since the shaft 13 will not be rotated and taking the position of the gear 11 and sprocket gear 12, as seen in Fig. 5, it will be evident that the teeth 16 on the said gear 11 have just passed the teeth 19 on the gear 12, and the faces 18 and 17 are sliding upon each other, so that no action will be imparted to the sprocket shaft 13 and thus to the sprocket wheels 14 and 15 and the conveyer will be stationary. When the gear 11 has rotated, in the direction indicated by the arrow thereon, in Fig. 5, a suitable distance, the teeth 16 will engage with the next set of teeth 19 of the gear 12 so that the shaft 13 will be rotated, carrying with it the sprockets 14 and 15 and the carrier will be advanced the required distance, which is predetermined, necessary to carry the required number of bottles beneath the filling means. As soon as they are in this position the next face 18 of the gear 12 will contact with the face 17, on the gear 11 and the chain will again remain stationary. As stated the required amount of movement of the carrier can be determined by providing the necessary number of teeth 16 in the gear 11 and the necessary amount of teeth 19 on the gear 12.

In the drawings I have shown in Fig. 1, four sets of filling means so that it will be necessary that four rows

of bottles be moved to the position beneath the fillers, held there the necessary time until filled and then removed from beneath the fillers and four more rows or sets of bottles placed beneath the fillers, while in Fig. 2, I have shown six sets or rows of bottles which must be placed beneath the filling means, in which event it will be necessary that six rows of bottles be removed and six new rows placed thereunder, at each movement of the chain.

From the above description it will be seen that the carrier is intermittently operated and that when the bottles are placed beneath the filling means, the carrier is halted a sufficient time until the bottles are filled.

I will now describe the operation of the filling means, it being understood, of course, that the two operations of actuating the carrier and of actuating the filling means are timed with respect to each other and the time of operation of each will be dependent upon each other. When power is imparted to the power wheel 4 it will actuate, as before described, the worm gear 8 and shaft 10. This carries the intermittent gear 20 and rotates the same. When the parts are in the position seen in Fig. 5 it will be understood that the set of teeth 21 in the gear 20 are about to engage one set of teeth 25 on the lifter gear 26 so that the latter are actuated in the direction indicated by the arrow with respect to said figure. This rotates the shaft 28 and carries with it the cranks 29 and crank pins 30. The crank pins, just before this movement takes place, are in the position seen in Fig. 4, that is at their highest point, but as the lifter shaft 28 is rotated the crank pins 30 are moved to their lowest point, carrying with them, the rod 31, collar 32 and rods 33. As these latter support the reservoir or tank 38, this will be lowered and carries with it the valves 41 and as the conveyor 45 meanwhile has been operated to place the necessary number of bottles beneath the valves, and as the heads 43 contact with the mouths of the bottles, the valves are opened and the fluid from the tank 38 is permitted to flow into the bottles, it being understood, however, that at this point the face 24 of the intermittent gear 20 has come into contact with the face 27 of the lifter gear 26 and a dwell on the shaft 28 is permitted, this being done in order to give the necessary time to permit the required amount of fluid to flow from the reservoir or tank into the bottles. As soon as the teeth 22 on the gear 20 contact with one set of the teeth 25, the shaft 28 is again rotated and the crank pins 30 are raised from their lowest position to the highest as seen in Fig. 4, when the tank 38 is again elevated, the valves automatically closing. At this point the faces 23 of the gear 20 will contact with one of the faces 27 of the lifter gear 26 so that a dwell is again given to the lifting and lowering mechanism, for the tank 38, so that the latter remains stationary in its elevated position, while the actuating means operates the carrier to remove the filled bottles 44 from their position beneath the filling means and a new set of empty bottles are placed thereunder.

From the above it will be understood, therefore, that by regulation of the mutilated faces on the gears any desired dwell can be given to the lifting and lowering mechanism so that the same can be raised and lowered and held in either its elevated or lowered position any desired length of time, the action of the carrier or conveyer being timed in accordance therewith.

As before stated I may employ any suitable form of valve which will be properly actuated when lowered and automatically closed as soon as removed from the mouth of the bottle and I may employ valves of any form and description. I would also have it understood that if necessary, I may operate these sprockets 2 and 3 either one or both, in a suitable manner so that the same are actuated in a similar manner to the sprockets 14 and 15.

10 Having thus described my invention, what I claim as new and desire to secure by Letters Patent, is:—

1. In a device of the character described, a tank adapted to receive the fluid, a plurality of valves carried by said tank and adapted to be opened when the same contact with the bottles and to automatically close when removed from contact therewith, mutilated gears suitably actuated adapted to raise and lower said tank and to allow the same to remain in its elevated or lowered position a predetermined time, a carrier adapted to receive the bottles, and mutilated gears suitably actuated adapted to move said carrier a predetermined distance and to allow the same to remain stationary during the act of filling.

2. In a device of the character described, a tank adapted to contain the fluid, a plurality of valves carried by said tank and adapted to suitably open and close, a mutilated gear adapted to actuate said tank to raise and lower the same and having plain faces thereon, making a dwell when the valve is in elevated position and when it is in lowered position, and a second mutilated gear having plain faces

30 mentioned gear at the proper time.

3. In a device of the character described, a tank adapted to contain fluid, a plurality of valves carried by said tank and adapted to be suitably opened and closed, a gear suitably supported, dwells on said gear, a second gear meshing with said first mentioned gear and having dwells adapted to contact with the dwells on the first mentioned gear, whereby said tank is raised and lowered and is held in its upper and lowermost positions a predetermined time by said dwells, a carrier, a sprocket meshing therewith, a shaft carrying said sprocket, a gear carried by said shaft and having dwells thereon, and a second gear meshing with said gear on said sprocket shaft and having dwells, said sprocket being adapted to move said carrier a predetermined distance and stop the same at a predetermined time.

4. In a device of the character described, a tank adapted to receive the fluid, a plurality of valves carried by said tank and adapted to be opened when the same contact with

50 the bottles and to automatically close when removed from contact therewith, rods carrying said tank, mutilated gears suitably actuated adapted to raise and lower said tank and to allow the same to remain in its elevated or lowered position a predetermined time, a carrier adapted to receive the bottles, and mutilated gears suitably actuated adapted to move said carrier a predetermined distance and to allow the same to remain stationary during the act of filling.

5. In a device of the character described, a tank adapted

to contain the fluid, a plurality of valves carried by said tank and adapted to suitably open and close, rods suitably supported and carrying said tank, a mutilated gear adapted to actuate said rods to raise and lower the same and having faces thereon, making a dwell when the valve is in elevated position and when it is in lowered position, and a second mutilated gear having plain faces adapted to contact with the plain faces of the first mentioned gear at the proper time.

6. In a device of the character described, a tank adapted to contain fluid, a plurality of valves carried by said tank and adapted to be suitably opened and closed, rods movably supported carrying said tank, a shaft with which said rods are suitably connected, a gear on said shaft, dwells on said gear, a second gear meshing with said first mentioned gear and having dwells adapted to contact with the dwells on the first mentioned gear, means for imparting motion to said last mentioned gear, whereby said tank is raised and lowered and is held in its upper and lowermost positions a predetermined time by said dwells, a carrier, a sprocket meshing therewith, a shaft carrying said sprocket, a gear carried by said shaft and having dwells thereon, and a second gear meshing with said gear on said sprocket shaft and having dwells, said sprocket being adapted to move said carrier a predetermined distance and stop the same at a predetermined time.

7. In a device of the character described, a tank adapted to contain fluid, levers pivotally connected with the frame of the machine and having pivotal connection with said tank, rods movably connected with said levers, guides for said rods, a shaft with which said rods are suitably connected, and means for imparting motion to said shaft in order to raise and lower said tank and to permit the same to remain a predetermined time in its raised and lowered position.

8. In a device of the character described, a tank adapted to receive the fluid, a plurality of valves carried by said tank and adapted to be opened when the same contact with the bottles and to automatically close when removed from contact therewith, mutilated gears suitably actuated adapted to raise and lower said tank and to allow the same to remain in its elevated and its lowered position a predetermined time, a carrier adapted to receive the bottles, and means suitably actuated adapted to move said carrier a predetermined distance and to allow the same to remain stationary during the act of filling.

9. In a device of the character described, a tank adapted to receive the fluid, a plurality of valves carried by said tank and adapted to be opened when the same contact with the bottles and automatically closed when removed from contact therewith, means suitably actuated adapted to raise and lower said tank and to allow the same to remain in its elevated and its lowered position a predetermined time, carrier adapted to receive the bottles, and mutilated gears suitably actuated adapted to move said carrier a predetermined distance and to allow the same to remain stationary during the act of filling.
